(57) CLAIM

The ornamental design for an article of jewelry for footwear, as shown and described.

DESCRIPTION

FIG. 1 is a front elevation view of an article of jewelry for footwear showing my design;

FIG. 2 is a rear elevation view thereof;

FIG. 3 is a right side perspective view thereof, the left side perspective view is a mirror image;

FIG. 4 is a front perspective view thereof, shown in a condition of use with a broken line shoe;

FIG. 5 is a left side perspective view thereof, shown in a condition of use with a broken line shoe, the right side perspective view is a mirror image;

FIG. 6 is another front elevation view thereof, shown in a flattened position; and,

FIG. 7 is a left side perspective view thereof, shown in a flattened position, the right side perspective view is a mirror image.

The broken lines and the surface area between the broken lines in the drawings form no part of the claimed design. The surface area between the bottom solid line edge of the individual flaps and the first broken line above the bottom solid line edge is unclaimed.
